SNATCH BLOCK

William H. McKissick and Jesse E. Fate, Jr.,
Tulsa, Okla., assignors, by mesne assignments,
to William H. McKissick

Application February 3, 1943, Serial No. 474,594

11 Claims. (Cl. 254—193)

This invention relates to improvement in snatch blocks and more particularly to improvements in snatch blocks of the type disclosed in United States Patent 1,994,024. In that patent the becket is so connected to the side plates that the hook when in normal position cannot swing about a horizontal axis. This is a disadvantage which we eliminate in the present invention.

An object of the invention is to so mount the becket and hook with reference to one another that the becket can not be removed until the hook is detached therefrom.

Another object is to provide snatch blocks improved to facilitate the stringing or removal of the cable.

With the foregoing objects outlined and with other objects in view which will appear as the description proceeds, the invention consists in the novel features hereinabove described in detail, illustrated in the accompanying drawings and more particularly pointed out in the appended claims.

In the drawings:

Fig. 1 is a fragmentary side elevation, partly in vertical section, of one form of snatch block including our improvements.

Fig. 2 is a similar view taken at right angle to Fig. 1.

Fig. 3 is a fragmentary side elevation partly in vertical section of another form of the invention and with the side plates in normal position.

Fig. 4 is a fragmentary side elevation of the same but with one side plate displaced relatively to the other to facilitate stringing of the cable.

Fig. 5 is a transverse vertical sectional view of the structure shown in Fig. 3.

Fig. 6 is a view similar to Fig. 5 of the upper portion of the block with an addition thereto.

Fig. 7 is a side elevation of still another type of snatch block and containing a form of our improvements.

Fig. 8 is an edge view of the block shown in Fig. 7, partly in transverse vertical section.

Referring to the block shown in Figs. 1 and 2, 9 designates the sides or side plates of a snatch block, between which there is journaled a conventional sheave 10. A tube 11 is positioned horizontally between the side plates and provided with end flanges 12 which abut the latter. The tube is provided with an arm 13 pivotally secured at 14 to one of the side plates. In order to secure the tube in normal position a bolt 15 extends therethrough and is secured to the side plates.

A becket 16, preferably of stirrup shape, has an opening or window 17 of a size to pass over one

of the flanges 12 in placing the becket on or removing it from the tube 11, and from Fig. 1 it may be seen that the upper portion of the becket is provided with an arc shaped bearing surface 18 which slides on the tube 11 between the flanges 12. The lower end of the becket is provided with a vertical aperture 19 to rotatably receive the shank 20 of a hook 21, depending from the becket. The shank may be secured to the becket by any suitable means but we prefer to thread a portion of the shank so that it can cooperate with a nut 22 positioned in the becket. The nut may be fixed to the shank by any suitable means to prevent accidental unscrewing of the shank and when the nut is in operative position it will rotate on the bottom portion of the becket to allow swivelling of the hook.

In assembling the parts, if we assume that the bolt 15 is removed, and the arm 13 is hanging downwardly from its pivot 14, the becket can be readily placed onto the tube 11 and then the tube can be raised to the position shown in Fig. 1, and the bolt 15 can be replaced. Before elevating the becket, the nut 22 can be introduced into the window 17 and subsequently the shank of the hook may be screwed into the nut.

In the embodiment of the invention illustrated in Figs. 3 to 5 inclusive, the sheave 23 is journaled between the side plates 24 and the connecting means is such as to allow one plate to swing about the axis of the sheave, as indicated in Fig. 4. The tube 25 in this example, is fixedly secured to one of the side plates, by any suitable means, such as welding 26, and a stationery nut 27 is secured to the opposite side of the same plate by welding 28. Here also the tube has end flanges 29 forming a saddle for the top portion 30 of the becket 31. When one of the side plates is swung upwardly as indicated in Fig. 4, it is obvious that the cable may be inserted in the groove of the sheave. When the plates are in normal position a screw 32 passes through the plates and tube and has threaded engagement with the nut 27. In this form of the invention a nut 33 is used to hold the shank of the hook 34 in swivel engagement with the becket.

With certain types of snatch block, as shown in Fig. 6, a member 35 of U-shaped cross section may be pivotally secured to the axle 36 of the sheave by means of nuts 37 having threaded engagement with the ends of the axle. An eye 38 or the like may be connected to the cross portion of the part 35.

In the modification shown in Figs. 7 and 8, one end of a cross bar 39 is hingedly connected to

one of the side plates as indicated at 40 and the opposite end of the cross bar is detachably secured to the other plate by means of a bolt 41. The cross bar forms a saddle for the upper end portion of the becket 42 to rock on. In this structure, like in the others, the shank of the hook 43 is swivelled in the becket and secured in place by a nut 44 or its equivalent.

Manifestly the various snatch blocks disclosed may be made of any suitable material such as metal and each form is constructed to facilitate the placing of a cable on or removal of a cable from the sheave. In Figs. 1 and 2, this would be accomplished when the bolt 15 is removed and the arm 13 is hanging down. In Figs. 3 to 6 inclusive, this can take place when the parts are in the position shown in Fig. 4, and in Figs. 7 and 8 this can be performed when the bolt 41 is removed and the bar 39 hangs down.

While we have disclosed what we now consider to be preferred embodiments of the invention, it will be apparent to those skilled in the art that changes may be made in the details disclosed without departing from the spirit of the invention as expressed in the claims.

What we claim and desire to secure by Letters Patent is:

1. In a snatch block of the type having opposite sides with a sheave journaled between them, a tube arranged between the sides, an arm fixed to the tube and pivotally connected to one of the sides to allow the tube to be swung toward and away from a normal position, means extending through the tube and connecting the same to the sides for supporting the tube in normal position, said tube forming a saddle, a becket having its upper portion rockably mounted on the saddle for movement about a horizontal axis, a hook depending from the becket and having a shank swivelled in the bottom portion of the becket for movement about a vertical axis, and a member secured to the shank and rotatably arranged in the becket for supporting the hook.

2. In a snatch block of the type having opposite sides with a sheave journaled between them and in which one of the sides is adapted to turn relatively to the other side about the axis of the sheave, a tube fixedly secured to the inner surface of one of the sides, a nut fixedly secured to the opposite surface of the last mentioned side, a screw extending through the opposite side and the tube and having threaded engagement with said nut, a becket rockably mounted on the tube for movement about a horizontal axis, a hook having a shank swivelled in the becket for movement about a vertical axis, and a member arranged in the becket and secured to the shank for supporting the hook.

3. A snatch block is claimed in claim 2 in which a connecting member of substantially U-shape is operatively connected to the sides by means coaxial with the axis of the sheave.

4. In a snatch block of the type having opposite sides with a sheave journaled between them and in which one of the sides is adapted to turn relatively to the other side about the axis of the sheave, a tube having an end fixedly secured to one of the sides and its other end extending toward the other side, threaded means arranged at the first mentioned end of the tube, a screw extending through one of the sides and tube and having threaded engagement with said threaded means, a becket rockably mounted on the tube for movement about a horizontal axis, a hook having a shank swivelled in the becket for movement

about a vertical axis, and a member arranged in the becket and secured to the shank for rotatably supporting the hook.

5. In a snatch block of the type having opposite sides with a sheave journaled between them and in which one of the sides is adapted to turn relatively to the other side about the axis of the sheave, a tube fixedly secured to the inner surface of one of the sides, a nut, a screw extending through the opposite side and the tube and having threaded engagement with said nut, a becket rockably mounted on the tube for movement about a horizontal axis, a hook having a shank swivelled in the becket for movement about a vertical axis, and a member arranged in the becket and secured to the shank for supporting the hook.

6. In a snatch block of the type having opposite sides with a sheave journaled between them, 20 a support connecting said sides, said support having an enlargement at one end thereof, a becket detachably mounted on and rockably supported by said support for free movement about a horizontal axis, the becket having an aperture therein to receive said support and the aperture being 25 larger at one side than the other, the larger side of the aperture being of sufficient size to permit the becket to slip over said enlargement and the smaller side of the aperture being of insufficient 30 size to allow the becket to be slipped over said enlargement, a hook depending from the becket and having a shank swiveled in the bottom of the becket for movement about a vertical axis, and a support element secured to the shank and 35 rotatable in the aperture on the lower portion of the becket, said support element normally preventing the support from moving into the larger side of the aperture.

7. In a snatch block of the type having opposite 40 sides with a sheave journaled between them, a tube arranged between the sides, said tube having an enlargement at one end thereof, means connecting the tube to the sides, said tube forming a saddle, a becket having its upper portion 45 rockably mounted on the saddle, said becket having an aperture to receive said tube and the aperture being larger at one side than the other, the larger side of the aperture being of sufficient size to permit the becket to be slipped over the 50 enlargement and the smaller side of the aperture being of insufficient size to allow the becket to be slipped over said enlargement, a hook depending from the becket and having a shank swiveled in the lower portion of the becket for movement 55 about a vertical axis, and a support member in the becket, secured to the shank and rotatably supported by the becket, said support member being arranged in the aperture and normally preventing the tube from entering the larger side 60 of said aperture.

8. In a snatch block of the type having opposite sides with a sheave journaled between them, a tube arranged between the sides and having flanged ends, means securing the tube to the 65 sides, a becket having its upper portion rockably mounted on the tube between its flanged ends for movement about a horizontal axis, the becket having an aperture therein to receive said tube and the aperture being larger at one side than the other, the larger side of the aperture being of sufficient size to permit the becket to be slipped over one of the flanged ends of the tube and the smaller side of the aperture being of insufficient size to allow the becket to be slipped over 70 said flanged end, a hook depending from the 75

becket and having a shank swiveled in the lower portion of the becket for movement about a vertical axis, and a member secured to the shank and arranged in the becket for rotatably supporting the shank, said member being arranged in the larger side of the aperture and normally preventing the tube from entering the larger side of the aperture.

9. In a snatch block of the type having opposite sides with a sheave journaled between them, a bar hingedly connected to one of said sides and having an enlarged end, means detachably connecting the enlarged end of the bar to the opposite side, said bar forming a saddle, a becket having an upper portion rockably mounted on the saddle for movement about a horizontal axis, the becket having an aperture therein to receive the bar, and the aperture being larger at its lower side than at its upper side, the larger side of the aperture being of sufficient size to allow the becket to slip over the enlarged end of the bar and the smaller side of the aperture being of insufficient size to allow the becket to be slipped over the enlarged end of the bar, a hook having a shank swiveled in the lower portion of the becket for movement about a vertical axis, and means in the becket between the bar and the lower portion of the becket for securing the shank to the latter, said means normally preventing the bar from entering the larger side of the aperture.

10. In a snatch block of the type having opposite sides with a sheave journaled between them, supporting means secured to the sides and forming a saddle, a substantially stirrup-shaped becket having one side portion engaging the saddle for free movement at any time about a horizontal axis, said supporting means being of rod-like form and having an enlargement at one end thereof, the becket having an aperture therein to receive said supporting means and the aper-

ture being larger at one side than the other, the larger side of the aperture being of sufficient size to permit the becket to be slipped over the enlargement and the smaller side of the aperture being of insufficient size to allow the becket to be slipped over said enlargement, a hook having a shank swiveled in the opposite side portion of the becket for movement about a vertical axis, and a nut arranged in the becket and having threaded engagement with the shank, said nut normally preventing the supporting means from moving into the larger side of the aperture.

11. In a snatch block of the type having opposite sides with a sheave journaled between them, a horizontal support connecting said sides and having an enlarged end, a substantially stirrup shaped becket detachably mounted on said support and having a single opening therethrough provided at one side with an arc-shaped surface and at the opposite side with a supporting surface, the opening at the arc-shaped side of the becket being smaller than at the side having the supporting surface, said arc-shaped surface engaging said support and being freely rockable thereon at all times, the larger side of the opening being of sufficient size to permit the becket to be slipped over the enlarged end of the horizontal support, and the smaller side of the opening being of insufficient size to allow the becket to be slipped over the enlarged end of the support, a hook extending from the becket and having a shank swiveled in one side of the becket for movement about a vertical axis, and a support arranged in the opening of the becket, secured to the shank and rotatable in contact with said supporting surface of the becket, the last-mentioned support normally preventing the horizontal support from entering the enlarged side of the opening.

WILLIAM H. McKISSICK.
